UNITED STATES PATENT OFFICE.

TRUMAN C. WEST, OF PETAL, MISSISSIPPI.

FRAME FOR CULTIVATORS OR HARROWS.

No. 920,408.

Specification of Letters Patent.

Patented May 4, 1909.

Application filed October 5, 1908. Serial No. 456,233.

To all whom it may concern:

Be it known that I, TRUMAN C. WEST, a citizen of the United States, residing at Petal, in the county of Forest and State of Mississippi, have invented a new and useful Frame for Cultivators or Harrows, of which the following is a specification.

This invention has relation to frames for cultivators or harrows, and consists in the novel construction and arrangement of its parts, as hereinafter shown and described.

The object of the invention is to provide a frame of the character indicated which is adapted to support a pair of adjustable bars in such manner that they may be pitched at desired angles with relation to each other, or may be brought into alinement with relation to each other transversely across the frame or diagonally with relation thereto. The said bars are adapted to carry harrow teeth or cultivator standards, as desired, whereby the implement of which the frame forms a part may be readily transformed from a harrow into a cultivator, or vice versa.

With these and other objects in view, the frame consists of the novel construction as hereinafter pointed out.

In the accompanying drawings:—Figure 1 is perspective view of the frame, with spring harrow teeth attached thereto. Fig. 2 is a perspective view showing the manner of applying a standard to the frame. Fig. 3 is a perspective view showing the manner of applying inflexible harrow teeth to the frame.

The frame consists of the beams 1, which are in juxtaposition, and which come together at their rear ends, and also lie against each other at their forward end portions. The clevis hook 2 is pivotally mounted between the forward ends 3 of the beams 1 and may be adjusted vertically therebetween. The rear portions of the beams 1 are spaced apart from each other, forming a slot 4 and the rear ends of the beams lie against each other. The braces 5 are substantially semi-circular in shape and are attached at their ends to the outer sides of the beams 1. The forward ends 0 of the braces 5 are connected with the beams 1 in advance of the forward end of the slot 4, while the rear ends of the said braces 5 are connected with the outer sides of the beams 1 behind the rear end of the slot 4. The said 5 braces 5 are provided upon their under edges with the notches 6. While the braces 5 are

shown and described as being semi-circular, they may be of any other desired configuration. The forward ends of the handles 7 are connected with the forward ends of the 60 braces 5 and also with the intermediate portions of the beams 1. The handle braces 8 are connected at their upper end portions with the handles 7, while the lower ends of the said braces 8 are connected with the rear 65 end portions of the braces 5.

The bars 9 are substantially U-shaped in configuration and are provided at their forward edges with the notches or recesses 10. The bolts 11 pass transversely through the 70 legs of the bars 9 and serve as means for clamping the sides of the said bars against the edges of the braces 5 and the beams 1. The inner ends of the bars 9 are pivotally mounted upon the upper end portion of the 75 standard 12, the upper end of which is formed into a bolt extremity 12' passes through the slot 4 provided at the rear end portions of the beams 1. The bolt 13 also passes through the slot 4 and is located behind the standard 12. 80 The inner ends of the arms 14 are pivotally connected with the lower portion of the bolt 13 and the said arms 14 extend parallel with the lower portions of the bars 9. The upper ends of the standard 12 and the bolt 13 are 85 screw-threaded and the taps 15 and 16 respectively engage the threads of the said standard and bolt. The standards 17 are pivotally connected at their upper ends with the legs of the bars 9 and are located beyond 90 the outer sides of the beams 1. Each of the standards 17 is provided with a brace 18 which is pivotally connected at its upper end with that arm 14 lying upon the side of the frame upon which the respective standard 17 95 is located. Suitable plow-points or shovels, (not shown) may be attached to the lower ends of the standards 12 and 17, and, if desired, the said shovels or points may be dispensed with, and harrow teeth may be located in the recesses 10 provided at the forward edges of the bars 9 and held therein by suitable clamping means. As illustrated in the drawings such a clamping means may consist of a link 19, which is adapted to lie 100 between the opposite sides of the bars 9 and which at one end receives the harrow tooth 20, and at its other end receives a pin 21, which is adapted to be forced vertically 105 against the rear edges of the bars 9. Or, instead of the teeth 20, the spring-harrow teeth 22 may be employed, and the said 110

teeth 22 are bolted at their forward ends to the under side of the bars 9 by means of the bolts 11, and are pivotally connected at intermediate points with the arms 14.

5 From the above description it is obvious that the bars 9 may be swung into alinement with each other transversely across the frame, or they may be swung into alinement at an oblique relation to the frame. It will 10 also appear that the said bars 9 may be pitched at an angle to each other, and, when properly positioned, may be secured in such position by means of the clamping bolts 11 and the taps carried thereby. As a means 15 to further assure the proper seating of the bars 9 upon the frame with relation to each other, the clips 23 may be employed, which are adapted to straddle the outer end portions of the said bars and pass down along 20 the sides of the braces 5. The said clips are provided at their lower ends with the hooks 24, which are adapted to engage the notches 6, provided in the lower edges of the braces 5, and the said clips are further provided at 25 their intermediate sections with the set screws 25, which are adapted to impinge against the upper sides of the bars 9. When the said clips 23 are in position upon the braces and bars as above described, it is ob- 30 vious that said bars will be positively held against any edgewise or lateral movement as a consequence of strain or otherwise.

Having described my invention, what I claim as new, and desire to secure, by Letters 35 Patent, is:

1. An agricultural implement frame com-

prising beams connected together at their rear ends and at their forward end portions, and being spaced at their rear portions, forming a slot, outwardly disposed braces secured 40 at their ends to the outer sides of the beams and encompassing said slot, a bar transversely disposed with relation to the braces and the spaced portions of the beams, earth-engaging 45 members carried by the bar, and a securing device passing through the bar and the slot formed at the rear portions of the beams.

2. An agricultural implement frame comprising beams connected together at their rear ends and at their forward end portions, 50 and being spaced at their rear portions, forming a slot, outwardly disposed braces secured at their ends to the outer sides of the beams and encompassing said slot, a bar transversely disposed with relation to the braces 55 and spaced portions of the beams, earth-engaging members carried by the bar, a securing device passing transversely through the bar and through the slot at the rear portions of the beams, and also secured at their forward ends to the beams in advance of the slot, and braces supporting the rear portions of the handles upon the rear portions of the first said braces.

In testimony that I claim the foregoing as 65 my own, I have hereto affixed my signature in the presence of two witnesses.

TRUMAN C. WEST.
